Inventor

Charles R. Edwards

Attn:

Hardway & Carter

UNITED STATES PATENT OFFICE.

CHARLES R. EDWARDS, OF HOUSTON, TEXAS.

DEVICE FOR UNSCREWING AND WITHDRAWING PIPE.

Application filed November 18, 1921. Serial No. 516,173.

This invention relates to new and useful improvements in an unscrewing device for pipe joints.

One object of the invention is to provide a device of the character described adapted for the purpose of unscrewing and withdrawing sections of a pipe which may become stuck in a well bore.

Another object is to provide a device of this character which can be operated to back off, or unscrew joints of stuck pipe through the instrumentality of a stem or string of pipe whose sections are connected by right hand threads, thus dispensing with the necessity of keeping on hand a string of left hand threaded pipe. The device may be employed also for unscrewing and withdrawing casing, tubing, drill rods and the like.

A further feature resides in the provision of a device of this character which can be readily detached from the stuck pipe and withdrawn in case said pipe cannot be unscrewed.

A still further feature resides in the provision of a pipe unscrewing device capable of being used in a bore in which casing is set; or in an open hole, that is, in a hole without casing.

A still further feature of the invention resides in the provision of a pipe pulling device whereby an upward pull may be exerted on the pipe to be pulled as the device is being operated to unscrew a section or sections of said pipe, to the end that the threads connecting the sections of the pipe to be pulled will be relieved of the weight, or a part of the weight of the sections above each joint so that the threads will more readily unscrew and it is clear that the threads of any particular joint will thus be subjected to less strain than the threads of the joint above it, since they will carry less load and the string of pipe being removed will thus be more liable to unscrew at one of its lower joints thus usually accomplishing the removal of a long string of sections of the pipe to be recovered.

With the above and other objects in view the invention has particular relation to certain novel features of construction, operation and arrangement of parts an ex-

ample of which is given in this specification and illustrated in the accompanying drawings, wherein:

Figure 1 is a vertical sectional view of the lower part of the device.

Figure 2 is a vertical sectional view of the upper part thereof.

Figure 3 is a transverse sectional view taken on the line 3—3 of Figure 1.

Figure 4 is a transverse sectional view taken on the line 4—4 of Figure 1.

Figure 5 is a transverse sectional view taken on the line 5—5 of Figure 1, and Figure 6 is a fragmentary sectional view.

Referring now more particularly to the drawings the numeral 1 refers to the upper section of a tubular enclosed casing employed and the numeral 2 refers to the lower section thereof, said sections being fitted together so as to form a close fitting joint 3, but being independently rotatable. The upper end of the section 1 is closed by a cap 4 screwed therein, and formed with a central bearing 5 in which a hollow shaft 6 rotates. The upper end of this shaft is threaded for engagement with the reducing collar 7, to which the stem is attached, through which the device may be rotated from the ground surface. The lower end of the shaft 6 carries annular flange 8 which works against the under side of an inwardly extending annular flange 9 carried by the lower section 2.

Seated in bearings in the casing there is a spider 10 through the central bearing 11 of which the shaft 6 extends. This spider may be made into two sections for easy assembling and has opposing bearings 12, 12 and 13, 13 spaced apart which receive the shafts 14, 14 and between the bearings 12 and 13 on each side the shafts 14 are provided with spur pinions 15, 15 which work in sockets provided for them in spider 10 shown in Figure 4 and are in mesh with the internal annular rack face 16 of the section 2. Said spur pinions 15 are likewise in mesh with a spur gear face 17 into which the opposing section of the shaft 6 is formed.

The upper ends of the shafts 14 also work in the opposing aligned bearings 18, 18 and 19, 19 of the spider 20 which is seated in

bearings in the section 1 and cap 4, and preferably made of two sections for easy assembly, and said ends of said shafts, between said bearings, carry spur pinions 21, 21 which work snugly in bearing pockets provided for them and are in mesh with the spur gear 22 into which the opposing section of the shaft 6 is formed and are also in mesh with the internal rack face of an annular sleeve-like friction member 23 which fits closely within the section 1 and frictionally engages the same. Pivoted on the shafts 14 are the elongated links 24, 24, which work in a corresponding direction, and the free ends of these links are pivoted to opposing dogs 25, 25, said dogs being pivoted at opposing points to the inner wall of the section 1, by means of the bearing rods 26, 26. The operation faces of said dogs which engage with the pipe or walls of the bore may be serrated or otherwise formed so as to more readily engage with said casing or wall of the bore.

The lower end of the section 2 is provided with internal threads into which the grapple or fishing tool may be secured. This tool 50 may be of any conventional form and consequently has not been shown. Usually it consists of a threaded tap, which may be screwed into or over the section of pipe to be unscrewed and withdrawn. This tap has left hand threads so that it will engage when turned to the left. The fishing tool or grapple is keyed in the section 2 as shown in Figure 6.

The device may be first attached to a string of pipe whose sections are connected by means of collars or fittings having right hand threads, and then let down into the bore until the fishing tool contacts with the upper end of the section of the stem to be unscrewed. The string to which the device is attached is then rotated toward the right which will cause the spur pinions 15, 15 to turn toward the left, as indicated by arrows in Figure 4. The section 2 will be temporarily held against rotation, during this movement on account of the friction of the fishing tool with the pipe on which it is in contact, and the section 1 will be held against rotation by reason of its friction with the section 2 and with the friction member 23. The section 1, being thus held, will cause the spur pinions 15 to travel around the rack face 16 in the direction indicated by arrows in Figure 4, thus forcing the links 24 and the dogs 25 outwardly through the wide slots 27, 27 which are cut through opposing sides of the section 1, causing said dogs to engage with the casing wall, or in the absence of casing, with the walls of the bore. And the section 1 and spiders 10 and 20 will thus be held firmly against rotation in the bore. A continued rotation of the shaft 6 will be transmitted through the spur pinions 15

and 21 and the shafts 14 to the section 2, turning it in the opposite or left hand direction and causing the grapple to engage with the adjacent section of the stuck pipe. The device should be now slightly elevated to relieve the strain on the threads at some point below where it is desired to unscrew the stuck pipe, and rotated backwardly, thus unscrewing the same from the section underneath, and when unscrewed the same may be withdrawn from the bore.

Loosely pinned, at one end, to the dogs 25 are the platelike hoods 28, 28 loosely mounted, at one end, to the corresponding rod 26. Each hood has an arcuate slot 29 cut therethrough, through which the upper end of the corresponding pintle 30, connecting the link 24 and the dog 25, works. As the dogs 25 move outwardly the pintles engage against the outer ends of the slots 29 and carry the hoods outwardly, into the position indicated by dotted lines in Figure 5, and said hoods are stopped by the engagement of the upturned lugs 31, carried by the free ends thereof, with the wall of casing 1, at the upper ends of the slots 27. The hoods will thus prevent the collection of earth or other formation under the dogs to prevent their closing.

In some cases it is necessary to detach the device from the stuck pipe, in case the same cannot be unscrewed or withdrawn. The construction permitting the release of the device in such cases will now be described.

The shaft 6 has a tubular liner 32 extending therethrough, and slidable therein. The upper end of this liner is threaded into a plunger 33 which works in the collar 7. The plunger is formed of two sections, screwed together, and between the sections there is clamped the cup 34 forming a close fit in the collar 7. The plunger is limited in its upward movement by the ringlike nut 35 which is threaded into the collar 7.

This collar has a port 36 beneath the plunger to permit the escape of water as the plunger moves downwardly. The plunger has restricted water passageways 37 and 38 to permit the passage of water into the liner 32.

There is a plate 39 threaded into the lower end of the section 2 which carries a central stuffing box 40, and above this plate there is a disc 41 which is seated on the coil spring 42. This spring rests on the plate 39 and surrounds the tubular guide 43 which works through the stuffing box 40 and into the upper end of which the lower end of the liner 32 is seated. Anchored to opposing sides of the disc 41 are the dogs 44, 44 which work through opposing marginal notches 45, 45 in the ringlike nut 46 screwed into the section 2 above the disc 41. The upper ends of the dogs are inwardly turned and normally aligned above the marginal notches 130

47, 47 of the flange 8. When it is desired to release the unscrewing device from the stuck pipe the stem 6 is first rotated to the left to release the dogs 25 and the water 5 in the stem is put under pressure which will force the plunger 33 and liner 32 downwardly thus compressing the spring 42 and carrying the disc 41 and the dogs 44 downwardly until the inwardly turned ends of 10 said dogs rest in the notches 47. The dogs will be stopped in this position by means of the shoulders 48, 48, on the outer sides of said dogs 44, which contact against the stops 49, 49 of the section 2. The dogs 44, 15 in this position will lock the section 2 of the fishing tool against rotation relative to the section 1 and the entire device will then rotate to the right with stem, 6, since the stem 6 and section 2 are now locked together 20 as a unit, and therefore lock the pinions 14 against rotation about their axes, thus locking together sections 1 and 2. While thus rotated the dogs 25 having been forced back, by the slight backward turn 25 of the stem 6 into released position within the casing the fishing tap will be unscrewed from the stuck pipe and the entire device may then be withdrawn. If water pressure is not available a string of tools, or other 30 weight, may be let down onto the plunger 33 to force it downwardly for the purpose above explained.

It is further obvious that the tool may also be varied as to its mechanical structure, 35 and still be the same tool in use and results, but only changed in form.

While what I now consider a preferred form of the tool has been shown and described, I reserve the right to make such 40 modifications and mechanical changes therein as may be found desirable so long as they are comprehended within the scope of the appended claims.

What I claim is:—

45 1. A device of the character described including two independently rotatable members, a driving shaft, means operatively connecting said shaft with one of said members, whereby, the latter may be rotated reversely, with respect to the shaft rotation, engaging means carried by the other member and actuated by said rotating means into engagement with the walls of a bore, whereby said last mentioned member is anchored against rotation and means for locking said members against relative rotation.

50 2. A device of the character described including two independently rotatable members, a driving shaft having bearings in said members, means operatively connecting said shaft with one of said members whereby the latter is rotated from the shaft, engaging devices carried by the other member and actuated by said means into engagement with the wall of a well bore whereby said last

mentioned member is anchored against rotation, and means arranged to be actuated by fluid or other pressure to lock said members against relative rotation.

55 3. A device for unscrewing pipe in a well bore, including a casing formed of two independently rotatable sections, a driving shaft, extending through the casing and having bearings in the respective sections thereof, engaging members carried by one of said sections an annular member in frictional engagement with the last mentioned section, means operatively connecting said shaft with said engaging members and with said friction member, said means being actuated by 60 said shaft to force said engaging members into engagement with the walls of the bore whereby the section carrying the same is anchored against rotation, and the continued 65 rotation of said shaft thereafter operating through said means to rotate the other section reversely with respect to the direction of the rotation of said shaft.

70 4. A device for unscrewing pipe in a well bore, including a casing formed of two independently rotatable sections, a driving shaft extending through the casing, engaging dogs carried by one section of the casing, means operatively connecting said shaft with said dogs whereby the rotation of the shaft relative to the casing will actuate said dogs into engagement with the well bore, and means through which the said sections may be 75 locked to rotate as a unit.

75 5. A device of the character described including two independently rotatable members, a driving shaft, means operatively connecting said shaft with one of said members whereby the latter may be rotated reversely 80 with respect to the shaft rotation, engaging means carried by the other member and arranged to engage with the walls of a well bore, whereby said last mentioned member is anchored against rotation, and means for locking said members against relative rotation.

85 6. A device of the character described including two independently rotatable members, a driving shaft, means operatively connecting said shaft with one of said members whereby the latter may be rotated reversely 90 with respect to the shaft rotation, engaging means carried by the other member and arranged to engage with the walls of a well bore whereby said last mentioned member is anchored against rotation, and means arranged to be actuated by pressure to lock said members against relative rotation.

95 7. A device of the character described including two independently rotatable members, a driving shaft, means operatively connecting said shaft with one of said members whereby the latter may be rotated reversely 100 with respect to the shaft rotation, engaging means carried by the other member

and arranged to engage with the walls of a well bore whereby said last mentioned member may be anchored against rotation, and protecting hoods arranged over said 5 engaging means.

8. A device of the character described including two independently rotatable members, a driving shaft, means operatively connecting the shaft with one of said members 10 whereby the latter may be rotated reversely with respect to the shaft rotation, engaging means carried by the other member and arranged to be projected out into engagement with the wall of a well bore whereby said 15 last mentioned member may be anchored against rotation and protecting hoods arranged to cover said engaging means, from above, when said means are in projected position.

9. A device for unscrewing and withdrawing pipe from a well bore, including a driving member, an anchorable member, means whereby said anchorable member may be anchored, and released, a driven member, a 20 releasable grapple attached to said driven member, means whereby said driven member may be rotated reversely so as to unscrew the joints of said pipe, and operative means whereby said grapple may be detached from a pipe in the bore.

10. A device of the character described including a driving member, an anchorable member, operative means for actuating said anchorable member, a driven member, operative means through which said driven member may be driven from the driving member, a grapple carried by the driven member, means for releasing said grapple, said device being formed with a fluid passage-way through which pressure may be exerted to actuate said releasing means.

11. A device of the character described including a rotatable driving member, an anchor, operative means whereby said anchor may be secured against rotation, a driven member, operative means through which said driven member is rotated from the driving member, said means including gears having both ends mounted in bearings formed in the same element of the device.

12. A device of the character described including a driving member, an anchor, operative means whereby said anchor may be fixed in position in the well bore, or released, a driven member, operative means through which said driven member may be rotated reversely with respect to the driving member, the contact of said driving member with the last mentioned operative means, being integral with the driving stem of the driving member, and means whereby the said driving and driven members may be interlocked so as to revolve as a unit.

13. A device for removing pipe and the like from a well bore, including a driven

member, a driving member rotatably mounted in said driven member, operative means through which the driven member is rotated reversely with respect to the rotation of the driving member, an anchor, means whereby said anchor may be fixed in position in a well bore, or released, a grapple actuated from the driven member, and means whereby said grapple may be detached from a struck pipe in a well bore.

14. A device of the character described including a driving member, an anchor, means whereby said anchor may be fixed in a well bore, or released, said means including engaging elements having toothed engaging faces, a driven member and means through which said driven member may be rotated reversely or conversely with respect to the rotation of the driving member.

15. In an unscrewing device of the character described, a grappling tool secured thereto, means through which the grappling tool is secured in place, said means preventing the detachment of said grappling tool from said device, and means whereby said grapple may be rotated either to the left or to the right.

16. In an unscrewing device of the character described a grapple secured thereto, a key preventing the detachment of the grapple from the device, and means whereby said grapple may be released from the pipe while the pipe is stuck in a well bore.

17. In an unscrewing device of the character described, an anchoring member having toothed engaging projections.

18. In an unscrewing device of the character described, driving pinions having both ends fitted in bearings formed in the same element of the device.

19. In an unscrewing device of the character described, driving pinions supported throughout their entire length in bearings, held in alignment as a unit construction.

20. In an unscrewing device of the character described a driving member formed with an integral driving gear, a grapple, means through which rotation may be imparted in either direction to said grapple from said driving member and means through which the parts of the device may be interlocked to rotate as a unit.

21. In an unscrewing device of the character described a driven member having a driving gear formed with gear teeth therein, a grapple adapted to be rotated in either direction through said teeth and means through which the device may be locked together to rotate as a unit.

22. In an unscrewing device of the character described, a grapple, a housing member having an internal gear formed integrally therewith and through which said grapple may be rotated and means through which the grapple may be locked against rotation by

said gear, whereby the entire device may be rotated as a unit, and the grapple released from the pipe stuck in a well bore.

23. In an unscrewing device of the character described, the combination of a driving member, a driven member and an anchorable member, one having pinions and formed with pockets in which said pinions rotate, a grapple carried by one of said members and operative means whereby the grapple may be attached to or detached from a pipe in a well bore, and means through which the said members may be interlocked to rotate as a unit.
24. In an unscrewing device a driving member, a driven member and an anchorable member, one of which is formed with pockets, pinions formed with pinion shafts and pinion teeth located in the pockets of said member, said pockets forming bearings for said shafts, the other members being formed with gear teeth with which said pinions are in mesh, and means through which said members may be locked together to rotate as a unit.

25. A device of the character described including two independently rotatable members, means for anchoring one of said members against rotation, a driving shaft and means for locking said members against relative rotation.

26. A device for unscrewing pipe in a well bore including a driving member, two rotatable members associated therewith, means whereby one of said rotatable members may be anchored against rotation, means through which the other of said rotatable members may be rotated reversely with respect to the driving member, a grapple carried by the member last named and means

whereby the grapple carrying member and the grapple may be rotated in the same direction as the driving member when supported by said driving member.

27. A device for unscrewing pipe in a well bore including an anchorable member, means whereby said anchorable member may be anchored against rotation, a driving member, a driven member, a grapple carried by the driven member, means whereby said driven member may be rotated reversely while supported by said driving member and means adapted to interlock the driving member and driven member whereby the entire device may be rotated as a unit.

28. A device for unscrewing pipe and the like in a well bore and including an anchorable member, a driving member formed with a stem, a driven member, a grapple carried by the driven member, means whereby said driven member and grapple may be rotated reversely with respect to the rotation of the stem while supported through said stem and interlocking means whereby said driven member and grapple may be locked to rotate as a unit with the stem.

29. In an unscrewing device of the character described, pinions, a supporting member having bearings for said pinions, and also formed with bearing like pockets, against the walls of which the outer ends of the pinion teeth contact for support.

30. In an unscrewing device of the character described, driving pinions having end bearings, and located in pockets whose walls form bearings for the pinion teeth.

In testimony whereof I have signed my name to this specification.

CHARLES R. EDWARDS.
